CLAMP DAGGER CAM RELEASE

Glenn E. Stilwell, Riverside, Calif., assignor to
Food Machinery and Chemical Corporation,
San Jose, Calif., a corporation of Delaware

Application September 23, 1948, Serial No. 50,729

12 Claims. (Cl. 1—10)

1

This invention relates to dagger or wedge cams and is particularly useful in nailing machines.

Such machines are widely used for making crates and boxes of wood and the invention is disclosed herein as embodied in a nailing machine in which the work is inserted, manipulated during the operations of the machine thereon, and removed by hand.

This particular type of nailing machine is known as a semi-automatic crate maker. In it a complete box is made by a series of three consecutive nailing operations. The first nails one side on the box heads. The second nails on the bottom. The third nails on the second side. The heads are automatically clamped in proper parallel spaced relation, during each nailing operation, by dagger-cam-actuated clamps. During the intervals between the first and second operations and the second and third operations the operator must rotate the work 90° and insert additional box parts. During the interval between the finishing of one box and the starting of another, the operator must pull the first box out of the machine and insert the heads and first side of the next box to be made. Each of these intervals begins with the relaxing of said clamps for clamping the box heads.

It is an object of the present invention to increase the speed with which this type of machine can be operated by advancing the moment at which said clamps are relaxed following each nailing operation thereby permitting the operator an earlier start in his manipulation of the work, and consequently an earlier completion of such manipulation and beginning of the next nailing operation.

The past practice has been to actuate the box head clamps as the nail drivers start downward, and to relax said clamps when the drivers have returned almost to their upwardmost position.

It is a further object of the invention to provide a dagger cam release which will operate to relax said cam during each nailing operation immediately after the nails have been driven into the work, and approximately as the nail drivers are starting up from their lowermost position.

Yet another and broader object of the invention is to provide a cam follower release mechanism which will automatically release the follower of a cam immediately upon a reversal of the direction said cam is moving relative to said follower.

The manner of accomplishing the foregoing objects as well as further objects and advantages

2

will be made manifest in the following description taken in connection with the accompanying drawings in which:

Fig. 1 is a diagrammatic front elevational view of an "AC" nailing machine equipped for the manufacture of lug boxes and in which a preferred embodiment of the invention is incorporated.

Fig. 2 is a side elevation of Fig. 1.

Fig. 3 is a diagrammatic fragmentary horizontal cross sectional view taken on the line 3—3 of Fig. 1 and illustrates the clamping means of the invention at the beginning of a box nailing operation with the clamp means relaxed.

Fig. 4 is a view similar to Fig. 3 and illustrates the clamp means in clamping relation with the box heads.

Fig. 5 is an enlarged side elevational view of the release mechanism of the invention.

Fig. 6 is a cross sectional view taken on the line 6—6 of Fig. 5.

Fig. 7 is a diagrammatic fragmentary front elevational view of those elements of the machine shown in Fig. 1 which are directly involved in a box nailing operation in said machine with said elements positioned as they are just before starting a box nailing operation and with two box heads and the first side already inserted into the machine, the clamping means at this time being relaxed.

Fig. 8 is a view similar to Fig. 7 and illustrates how the clamping means is actuated to clamp the box heads immediately upon the initiation of the downward movement of the nailing means.

Fig. 9 is a view similar to Fig. 8 and illustrates the parts of said nailing machine as these are located at the instant of the driving of the nails into the work is completed.

Fig. 10 is a view similar to Fig. 9 and illustrates the relationship of the parts of the machine just after the nailing means starts upward and shows how the dagger cam release mechanism of the invention operates to release the clamp means almost immediately following the completion of the driving of the nails into the work.

Fig. 11 is an enlarged front elevational view of dagger cam release mechanism of the invention and a portion of the dagger cam and illustrates, in full lines, the position of the cam follower of the invention when this is disposed to transmit movement from the cam to the shiftable member and in broken lines the position of the cam follower when it has been actuated to free the shiftable member from the action of the dagger

cam thereby causing the clamp means to automatically release its grip on the box heads.

Fig. 12 is a horizontal sectional view taken on the line 12—12 of Fig. 11.

Referring specifically to the drawings, the preferred embodiment of the invention illustrated therein comprises a box making machine 30 which includes a frame 31, a drive mechanism 32, a nailing mechanism 33, and a work supporting and aligning mechanism 34.

The frame includes a base 35, side standards 36, a front top cross tie 37, a rear top cross tie 38, a front work table cross tie 39, and a rear work table cross tie 40.

The standards 36 have slide ways 41. They also have clamp brackets 42 and 43 extending rearwardly therefrom (see Figs. 2 and 3), these brackets having bearings 44, 45, 46 and 47. Also provided on the base 35 is a short motor standard 48 having a bearing 49, and a motor platform 50.

The drive mechanism 32 includes a motor 55 mounted on the platform 50 which is connected by a chain 56 to a clutch 57 mounted on a shaft (not shown) having a pinion (not shown) which meshes with a master gear 58 on a crank shaft 59 which journals in bearings 46 and 49. When the clutch 57 is thrown in by depressing a foot pedal 60, the crank shaft 59 is rotated for a single revolution.

This shaft has a crank 61 on the opposite end thereof from said master gear, pitmans 62 being pivotally connected to said crank and said master gear so as to be reciprocated by each rotation of the shaft 59.

Also mounted on the shaft 59 are chuck lifting cams 63 which are aligned with rollers 64 on rockers 65 fixed on a shaft 66 which journals in bearings 67. Extending upwardly from rockers 65 are links 68. The functions of links 68 will be made clear hereinafter.

Shaft 59 also has a pinion 69 which meshes with a gear 70, the latter being mounted on a vertical shaft 71, the function of which will be made clear hereinafter.

The nailing mechanism 33 includes a rectangular driver head 72 having studs 73 which extend outwardly through and slide in the slide ways 41. The pitmans 62 have spring cushion units 74 at their upper ends which pivotally connect with the studs 73. Slideable in vertical holes provided in opposite ends of the head 72 are guide shafts 75, the lower ends of which are secured to a rectangular chuck mounting frame 77.

Carried on this frame is a pair of banks of nail chucks 80 which are supplied with nails in a manner well known in the art by nail tubes 81 and a nail feeding mechanism (not shown).

Carried on the driver head 72 is a pair of banks of nail drivers 82 which slide vertically through the chucks 80 during each nailing operation to drive nails from these chucks into the work.

The work supporting and aligning mechanism 34 includes a pair of multiple anvils 85 which are automatically shifted laterally in a manner well known in the art by a cam mechanism 86 which is actuated by the shaft 71 with each revolution of the crank shaft 59 so as to place the anvils 85 in the proper positions for supporting the heads during the next nailing operation. Each of the anvils 85 includes a ledge 87 for supporting a box head during the first nailing operation; a ledge 88 for supporting said head during the second nailing operation; and a ledge 89 for

supporting said head during the third nailing operation.

The mechanism 34 also includes a clamping device 90 which has a shaft 91 fixedly mounted in bearings 44 and 46, and a shaft 92 slideably mounted in bearings 45 and 47 (see Fig. 3). These shafts extend through rigid clamp arms 93 and 94 and spring clamp arms 95 and 96. The arms 93 and 96 are fixed to the shaft 91 and are slideable on the shaft 92. The arms 94 and 95 are fixed on the shaft 92 and are slideable relative to the shaft 91.

The shaft 92 extends outwardly beyond the bearing 47 to receive a stiff coiled spring 97 and a collar 98 for retaining the same on said shaft. The opposite end of said shaft extends outwardly beyond the bearing 45 and has fixed thereon a base 100 of a cam release device 101 (see Figs. 5 and 6). The base 100 has a main bore 102 which snugly fits over the end of the shaft 92, and threaded holes 103 therein receive set screws 104 for securing the base 100 in place.

The base 100 also has upstanding ears 105 which are bored to receive a pivot pin 106 on which is pivotally mounted a cam follower 107. This cam follower includes an arm 110 having a bore 111 parallel with the pin 106 and at the opposite end of the arm therefrom for receiving a roller pin 112 on the opposite ends of which 30 are rotatably mounted follower rollers 113. A stop screw 114 is received in a threaded hole which extends vertically through the arm 110 to permit this screw to bear against the base 100 and provide an adjustable stop which determines the down position of the follower 107. A stop nut 115 retains the screw 114 in its adjusted position.

Adjustably fixed by cap screws 120 on the driver head 72 (see Figs. 1 and 2) is a dagger cam 121, the lower end of which has an elongated eye 122 through which the shaft 92 extends and on opposite sides of which the cam 121 is provided with cam faces 123. For the most part, the cam faces 123 are parallel with the direction of travel of the cam 121 but near their lower ends these faces are provided with shoulders 124. The cam 121 extends between the bearing 45 and the cam release device 101 with the shoulders 124 directly above and almost in contact with the rollers 113 when the machine 30 is in its normal position of rest.

Near the upper end of the eye 122, the dagger cam 121 is provided with a control lug 125, the function of which will be made clear hereinafter.

Clamped onto the shaft 91 is a side and bottom shock support 130.

The links 68 pivotally connect at their upper ends with clevises 131 provided on the chuck mounting frame 77 so that the vertical movement of this frame and the chucks 80 is controlled during the nailing operation through the links 68 by the cams 63.

The rigid clamp arms 93 and 94 have vertically yieldable flushers 135 provided thereon.

65 Operation

The cam release device 101 of the invention operates in identically the same way during each of the three nailing operations required in the manufacture of a box. The operation of this device therefore will be adequately disclosed by a description of the first of the nailing operations.

This begins with the parts of the machine 30 positioned as shown in Figs. 1, 2, 3 and 7. To

prepare for the first operation, the operator places box heads H in the machine as shown in Figs. 3 and 7 and inserts the first side S of a box into the machine so that this rests with its ends overlying the box heads and with its rear edge moved back against suitable stops provided on the shock support 30 . The anvils 85 are automatically located at this time so that the ledges 87 are in supporting relation with the box heads H as shown in Fig. 7.

The operator now presses his foot upon the pedal 60 , thus throwing in the clutch 57 and causing a single revolution of the crank shaft 59 . This causes a downward and upward reciprocation of the nailing mechanism 33 by the pitmans 82 . The result of this in the operation of the cam releasing device 101 is well illustrated in Figs. 3, 4, 7, 8, 9, 10 and 11.

With the device 101 and dagger cam 121 released at the beginning of the nailing operation as shown in Fig. 1, it will be seen that the initial downward movement of the dagger cam with the nail driver head 72 brings the shoulders 124 of the cam faces 123 against the rollers 113 and, in view of the screw 114 preventing downward movement of the arm 110 beyond a horizontal position, the device 101 and the shaft 92 on which this is fixed are shifted to move the rollers 113 outwardly where they rest against the vertical portions of the faces 123 during the balance of the downward movement of the dagger cam 121 .

The outward movement of the device 101 effected by the cam shoulders 124 operates the clamp device 90 as shown in Figs. 4 and 8 to clamp the box heads H in correct parallel, spaced relation for uniting these in the box to be made in the machine 30 . This clamping action shifts the vertically yieldable flushers 135 together to properly align the end portions of the first side S with the heads H as shown in Fig. 8. Continued downward movement of the nailing mechanism brings the chucks 80 into contact with the flushers 135 , depressing the latter as shown in Fig. 9 and placing the chucks in direct contact with the end portions of the side S . The nail drivers 82 now continue downwardly through chucks 80 to drive nails therefrom through the ends of the side S and into the heads H . The completion of this driving of the nails is effected with the driving mechanism in its lowermost position in which it is shown in Figs. 9 and 11 wherein the lug 125 is brought down into contact with the rollers 113 of the device 101 .

As the nailing mechanism starts upward from its lowermost position, just described, the rollers 113 carried by the arm 110 move upwardly with the dagger cam 121 , said rollers remaining in contact with the lug 125 until the clamp device 90 has been completely released from the action of the cam 121 and has relaxed its grip upon the box heads H as shown in Fig. 3. This action is completed by the time the device 101 has reached the broken line position in which it is shown in Fig. 11.

The principal function of the lug 125 is to prevent the clamp device 90 being released too quickly with a snap action which is noisy and harmful to the machine. This lug requires the device 101 to gradually release the clamp device 90 so as to cause the machine to operate smoothly. Nevertheless, the device 101 results in such an early release of the clamp device as to enable the operator to substantially increase his production with the machine 30 .

When the dagger cam 121 arrives in its uppermost position as the nailing machine 30 comes to

rest at the conclusion of the single nailing operation just described, the shoulders 124 are disposed just far enough above the device 101 to permit the follower 107 to rock downward by gravity into the horizontal operative position in which it is shown in Figs. 1, 2, 5 and 6, and in the full line representation thereof in Fig. 11.

What I claim is:

1. In a nailing machine the combination of: work clamp means; nailing means; means causing reciprocatory relative movement between said two means and including an approach phase for the driving of nails from said nailing means into said work, and a return phase concluding with said two means in spaced relation; means causing said clamp means to clamp the work to properly position the same for said nailing operation, said clamping taking place in response to an initial portion of said approach phase of said movement; and means responsive to and operative during an initial portion of said return phase of said movement for relaxing said clamping means to unclamp the work.

2. A combination as in claim 1 in which said clamp actuating means comprises a cam and cam follower operated by said relative movement, and in which said clamp relaxing means comprises a mounting for said cam follower which transmits to said clamp means motion received by said follower from said cam in said approach phase of said relative movement; and means shiftably connecting said follower with said mounting to cause said follower to be shifted with respect to said mounting by said cam upon the reversal in direction of said movement thereby freeing said mounting from constraint by said cam and relaxing said clamp means.

3. In a nailing machine, the combination of: anvil means for supporting a pair of box heads; means for coordinately clamping said heads in proper parallel spaced relation for the nailing of sides and a bottom thereon to form a box; a nailing means mounted above the work thus supported and clamped; means for reciprocating said nailing means downwardly and upwardly to nail said sides and bottom on said box head; a dagger cam provided on said nailing means and reciprocating therewith during each nailing operation; a shiftable member provided on said clamp means and responsive to an initial downward portion of the movement of said dagger cam with said nailing means to cause said clamp means to clamp said heads as aforesaid; and means responsive to said nailing means starting upwardly immediately following the completion of the driving of the nails into the work for automatically releasing said shiftable member from the action of said dagger cam, whereby said clamp means relaxes its hold on said box heads.

4. A combination as in claim 3 in which said releasing means comprises a cam follower pivotally mounted on said shiftable member; and a stop for limiting the downward swinging of said follower about its pivot to bring the line of contact between said follower and said cam into intersecting relation with a line passing through said pivotal axis and normal with the path of movement of said dagger cam.

5. In a nailing machine, the combination of: a work support; a nailing device spaced therefrom; means for causing relative movement between said device and said support to drive nails in said work, said movement being divided into approach and return phases; means on said work support for clamping said work including an actuating shaft lying perpendicular to the direc-

tion of the aforesaid movement; a cam release device on said shaft; a dagger cam carried by said nailing device and moving between said work support and said device during said approach phase to shift said device and said shaft and actuate said clamp means to clamp said work in proper alignment for receiving said nails; and an arm pivotally mounted on said device and extending from its axis toward said cam, whereby said arm is engaged by said cam during said approach phase to transmit movement to said device to actuate said clamp means, said cam operating through its engagement with said arm at the beginning of said return phase to swing said arm about said axis to relax said clamp means and release said work therefrom.

6. A combination as in claim 5 in which said cam follower arm carries rollers on the end thereof, said rollers engaging said cam; and a stop on said device permitting said arm to swing slightly past dead center in the direction which said cam moves relative to said device during said approach phase, said arm being close enough to dead center, however, that the friction between said cam and said rollers during an initial portion of the return phase is sufficient to rotate said arm past dead center in the opposite direction and away from said stop, thereby freeing said cam release device from constraint by said cam and causing said clamp means to release said work.

7. In a nailing machine, the combination of: work clamp means; nailing means; power means causing reciprocatory relative movement during each nailing cycle between said two means and including an approach phase for the driving of nails from said nailing means into said work, and a return phase concluding with said clamp means and nailing means in spaced relation; means responsive to the actuation of said power means to cause said work clamp means to clamp the work in proper position prior to the driving of nails therein by said nailing means; a member adapted to be moved in one direction by said power means during said approach phase and in the opposite direction during said return phase; and a device acted upon by said member and responsive to said movement of said member in said one direction to set said clamp means, said device being responsive to said reverse movement of said member, at the start of said return phase to relax said work clamp means, thereby releasing said work and freeing the same substantially throughout the return phase of said relative movement.

8. A combination as in claim 7 in which said member is a cam and said device includes a cam follower shiftably mounted thereon, the reversal of movement of said cam shifting said follower relative to said device thereby causing said de-

vice to shift relative to said cam whereby said device releases said clamp means.

9. A combination as in claim 8 in which a control lug is provided on said cam which engages and regulates the speed of shifting of said cam follower relative to said device to prevent too rapid, noisy action by said device in releasing said clamp means.

10. In a nailing machine, the combination of: work clamp means; nailing means; power means causing reciprocatory relative movement during each nailing cycle between said two aforesaid means, said movement in each of said cycles including an approach phase for the driving of nails from said nailing means into said work, and a return phase concluding with said clamp means and nailing means in spaced relation; a dagger cam mounted on said nailing means; a cam release device connected to said work clamp means, reciprocatory relative movement between said cam and device to cause the actuation of said clamp means being produced by said relative movement between said work clamp means and nailing means; a cam follower arm pivotally mounted on said device; and a stop on said device for halting rotation of said arm thereon in a position in which said arm is engaged by said dagger cam to shift said device to actuate said work clamp means to clamp the work in proper position for the driving of nails therein by said nailing means, said position of said arm being such that the frictional engagement between said arm and said cam, upon the reversal of said relative movement between said cam and said arm, causes said arm to rotate about its pivotal connection with said device, thereby releasing said device from pressure from said cam thereby relaxing said clamp means from clamping relation with said work.

11. A combination as in claim 10 in which roller means is provided on the extremity of said arm for engagement with said cam to reduce the friction between said arm and said cam.

12. A combination as in claim 11 in which a control lug is provided on said cam so as to move away from said device as said arm rotates relative to said device, said lug being in a position to block and control said rotation of said arm.

GLENN E. STILWELL.
